CARBONATED WATER BOTTLE FILLER

Reginald J. Dowling and Charles D. Davidson,
Seattle, Wash.

Application July 10, 1936, Serial No. 89,958

7 Claims. (Cl. 226—62)

Our invention pertains to carbonated water bottle fillers, and in particular to the type which can be attached to the edge of a table, a wall bracket, or the like, and need not be provided with the usual heavy stand or base which is characteristic of the floor type.

Carbonated water is largely dispensed in so-called siphon bottles. The actual cost of carbonating and refilling such bottles is negligible, but because the equipment for so doing, heretofore available, has been large and expensive, hence has only been installed in plants filling bottles in large numbers, it has been necessary to charge considerable amounts for each bottle. The cost of collecting and redistributing the bottles controlled the cost thereof. Nevertheless, many neighborhood stores, such as drug stores, have carbonating equipment in connection with soda fountains, and can recharge and refill such bottles at small cost (since no collection and redistribution is necessary) if equipment is available suitable to their needs. Generally speaking, our object is to provide equipment suitable to such needs, to the end that the price of the charged water to the consumer may be lessened.

Such a filler should be adapted to be quickly mounted for use or removed for storage, and should also be of small size and compactly built so that it may be stored in a small space. Although our machine is not at all cumbersome, it is nevertheless of rugged construction. Having few parts, however, it is economical to produce and will not readily get out of order.

Another object of our invention is to provide a carbonated water bottle filler which will protect the operator from being injured by flying glass in case the bottle being filled should break. The charged water is forced into the bottle under a considerable pressure, and if this pressure becomes sufficiently great the bottle will burst, and the pressure created will shatter the glass, driving it with considerable force.

To assist the operator it is a further object of our invention to provide mechanism for automatically maintaining a bottle in filling position, so that he can direct his entire attention to the filling operation, or may leave the machine without first removing the bottle from filling position.

Still a further object of our invention is to provide a filling machine which will accommodate carbonated water bottles having heads varying somewhat in size and shape without having to make any adjustments in the machine. To

adapt the machine for the reception of bottles having heads of widely different size or shape we provide regulating mechanism.

Other objects, and more particularly those which inhere in the simple though efficient construction which we employ, will appear from a study of the drawing and the ensuing description.

Our invention, then, relates to a carbonated water bottle filler, having among others the above mentioned advantages, an efficient, convenient and operative form of which is illustrated in the drawing and described hereafter in the specification. While this form shown and described is the one which we now prefer it will be understood that various changes in detail may be made without departing from the spirit and scope of our invention, as pointed out more particularly in the claims appended to this specification.

Figure 1 is a side elevation view of our device, showing a bottle in operative position and partly filled, but with the protective cage shown in inoperative position for better revelation of the parts.

Figure 2 is another elevation view taken along the line 2—2 of Figure 1.

Our device is of the bracket type which may be attached to a table, a wall or any similar structure. Upon the bracket 1 is mounted a filling faucet 2, which is spaced above the bracket a distance sufficient to receive therebetween the head 3 of a bottle B.

The bottle is supported from the bracket 1 chiefly through the medium of a block 4, which is formed to engage the solid end of the bottle head. This block is provided with some convenient means to raise and lower it so that the spout of the bottle 30 may be forced up into engagement with the faucet 2. Lifting means, which are simple and which we have found to be efficient for our purpose, may consist of a rod 40 which projects through and is guided by a hole extending through the bracket 1. The upper end of this rod is received in a recess 41 formed in the block 4. To move this rod lengthwise I 45 may provide a manually operated lever 42, having a suitable handle, which is journaled in the bracket upon a pivot bolt 43, extending transversely of the rod 40. On the pivoted end of this lever is formed an eccentric cam surface 44 which engages the lower end of the rod. Upward movement of the lever 42 causes this cam to rotate in a direction to raise the rod, which in turn will lift the block 4 and the bottle head 3 supported thereby to engage the spout 30 with the faucet 2. 55

It is very desirable that the operator be free to accomplish the filling operation without having his mind distracted by having to hold the bottle in place. Furthermore, it is desirable that the operator be at liberty to leave the machine temporarily to attend to other work. A machine of this type, for example, may be employed at a soda fountain or in a drug store. The operator in his spare moments or upon order may fill carbonated water bottles, and with a device which locks or maintains the bottle in place he may leave the machine at any stage of the filling operation to wait on a customer.

Frictional engagement of the lever 42 with the bracket 1 might serve this purpose, or a positive catch might be employed. As a preferred type of mechanism for accomplishing this operation, however, we form the surface of the cam 44 with a flat or other suitable portion 45 at the end 20 of its travel. When engaged with this portion of the cam surface the rod 4 will be in its upper position, wherein the spout 30 is held in engagement with the faucet 2, and the parts will be maintained thus disposed automatically, against 25 the force of gravity or weight of the bottle, the block 4 and the rod 30, and also against the pressure exerted by the head 3 against the block 4, in reaction to the pressure of the spout 30 against the faucet 2.

30 The tops of carbonated water bottles are not always of the same size or shape. For small variations in dimensions we provide an automatic adjustment. The travel of the rod 40 vertically is uniform for all bottle engaging operations. In positioning bottles of different sizes, however, the block 4 may be required to move varying distances to accommodate such bottles. To permit such movement of the block 4 we may interpose a spring 46 between the upper end of 40 the rod 40 and the bottom of the recess 41. As the movement of the block 4 is required to vary, when the rod 40 is in the upper position, the spring 46 will be increased or decreased in length. In every case, however, this spring will insure a 45 sufficient pressure of the spout 30 against the nozzle of the faucet 2 to provide a leak-proof connection.

For larger variations in bottle top size and shape it may be necessary to adjust either the 50 height or the lateral position of the faucet 2. The height may be adjusted by raising or lowering the faucet supporting column 20 which is guided in the bracket 1 and secured thereto by any convenient means such as a set screw 21. 55 Rotation of this column will cause the faucet to swing to any desired lateral position through an unlimited arc. To change the radius of swing of the faucet the set screw 22 may be loosened and the horizontal carbonated water supply pipe 60 23, acting as a supporting member, may then be slid in or out of the column 20 T, as desired, and secured in the new position. The faucet is thus given universal movement, both vertically and in every horizontal direction. With such adjustment the machine may be set to accommodate 65 bottles having heads of any size and shape within a wide range.

When a bottle B to be filled is to be put in place the lever 42 will be in the down position. The 70 bottle head 3 will then be set on the block 4, with the bottle body lying in a cradle member 5 which is supported upon an arm 50 inclined upwardly from and fixedly secured to the bracket 1. This arm lies in a vertical plane except for its 75 upper end, which is twisted into a plane normal

thereto to receive the cradle. The lever 42 is then raised, to raise the block 4 for lifting the bottle head to engage the spout 30 with the faucet.

Before the filling operation can be started the 5 lever 6, pivoted on the arm 50, must be turned to depress the handle 31 of the soda water bottle, so that the valve in the head will be opened to establish communication between the spout 30 and the tube 32 extending down into the bottle. 10 The filling operation is then accomplished by manipulation of the valve handle 24 to connect with the spout 30 either the carbonated water supply pipe 23 or a pressure relief or snifter pipe 25. 15

Considerable pressures are generated in carbonated water bottles, especially during the filling operation. Occasionally such pressures will cause a bottle to burst, and it is therefore desirable to provide means to protect the operator 20 from flying glass. For this purpose we provide a cage 7 which is constructed as a single piece. Several elements may be joined to make such a cage, of course, such as the cylindrical body, an insert 70 made of screen material, and a circular 25 end. Upon completion, however, the whole structure will constitute a single piece, having no hinges or clasps which might be subject to failure. Thus when the cage is inserted over the bottle B and the arm 50, as shown in dotted lines 30 in Figure 1, a bursting bottle will be confined positively, since there are no catches or the like which might spring open.

In inoperative position the protective cage 7 hangs downward out of the way, supported by a 35 ring 71 which slides over the arm 50 and may engage in a notch 51 formed therein. When the bottle has been put in place the cage may be lifted and the ring 71 slid upward to a position adjacent to the cradle 5. The cage is then tipped 40 into alignment with the arm and bottle and slipped down thereover, the ring 71 sliding back down the arm into the dotted line position shown. The ring is sufficiently large so that it will not unduly hamper movement of the cage lengthwise 45 of the arm, and the arm, it will be noted, terminates adjacent to the bottom of the bottle, so that lateral movement of the cage is not restricted when its open end has passed beyond the 50 bottle.

The described structure does not hold the cage 55 rigidly in place, so that in case the bottle breaks, the pressure generated will tend to lift the cage upwardly, the ring 51 permitting limited movement thereof outward toward the end of the arm 50. Since such movement will considerably cushion the bursting force within the cage, the explosion will have less tendency to rupture it. The 60 outward movement of the cage will be stopped by its interconnection with the arm through the ring 71, which cannot slide past the cradle 5. Thus while the peak stress on the cage will be greatly diminished and its protective quality will be increased correspondingly, the cage itself, with the glass pieces from the bottle contained therein, 65 can not be hurled from the machine to inflict injury.

It will be seen, therefore, that our machine 70 incorporates important features conducive to safe and efficient operation, although the structure is simple, compact and rugged.

What we claim as our invention is:

1. A carbonated water bottle filler comprising a bracket adapted to be mounted on a table or the like, a filling faucet held in position definitely 75

spaced thereabove, an upwardly inclined arm fixed to the bracket, adapted to support the body of the bottle, a block to engage the head of a carbonated water bottle, means guided by said bracket, supporting said block and operable to raise it, for raising the bottle head engaged thereby into operative engagement with the filling faucet, means cooperating with said first means to maintain such means automatically in position to hold the bottle in its upper, faucet-engaged position against the force of gravity and the pressure of the bottle head, and a lever pivoted on said fixed arm and engageable with the valve handle on the bottle head to depress the same only after said bottle head has been fully raised to its upper position by said cam lever.

2. A carbonated water bottle filler, comprising a bracket adapted to be mounted on a table or the like, a filling faucet held in position definitely spaced thereabove, an upwardly inclined arm fixed to the bracket, adapted to support the body of a bottle, an upright rod extending through and guided in said bracket for lengthwise movement, a block carried by the upper end of said rod above said bracket to engage the head of a carbonated water bottle, a hand lever journaled in said bracket upon an axis disposed transversely of said rod and directly in line therewith, having an eccentric cam formed on its journaled end to engage the lower end of said rod, by swinging of the lever to raise or to lower said rod, and in turn said block and the bottle head engaged thereby, said cam being formed to maintain the rod and lever in their upper positions against the force of gravity and the pressure of the bottle head, and a lever pivoted on said fixed arm and engageable with the valve handle on the bottle head to depress the same only after said bottle head has been fully raised to its upper position by said cam lever.

3. A carbonated water bottle filler, comprising a bracket adapted to be mounted on a table or the like, a filling faucet held in position definitely spaced thereabove, and upwardly inclined arm fixed to the bracket, adapted to support the body of a bottle, an upright rod extending through and guided in said bracket for lengthwise movement, a block carried by the upper end of said rod above said bracket to engage the head of a carbonated water bottle, a hand lever journaled in said bracket upon an axis disposed transversely of said rod and directly in line therewith, having an eccentric cam formed on its journaled end to engage the lower end of said rod, by swinging of the lever to raise or to lower said rod, and in turn said block and the bottle head engaged thereby, said cam being formed to maintain the rod and lever in their upper positions against the force of gravity and the pressure of the bottle head, yieldable means incorporated in said rod between said cam and said block, to accommodate the displacement of the block to receive bot-

tle heads of different sizes between it and said faucet, for unvarying movements of said rod and lever, and means to adjust the position of said filling faucet transversely in any direction or vertically to accommodate between it and the block 5 bottle heads varying greatly in size and shape.

4. A carbonated water bottle filler, comprising a bracket, an upwardly inclined arm fixed to said bracket, adapted to support the body of a bottle, a single piece protective cage of a size to enclose 10 both said arm and a bottle disposed adjacent thereto, stop means secured to said arm, and means connected to said cage and engageable with said stop means, to limit upward movement of the cage along the arm.

5. A carbonated water bottle filler, comprising a bracket, an upwardly inclined arm fixed to said bracket, adapted to support the body of a bottle, a single piece protective cage of a size to enclose 20 both said arm and a bottle disposed adjacent thereto, a supporting member secured to said cage and encircling said arm to slide upward thereon for insertion of said cage over the arm and bottle or for removal therefrom, and slidably down said arm for movement of said cage downward over the arm and bottle to cover them, or to support said cage hanging downward below said arm when in inoperative position, and stop means on said arm for engagement with said cage supporting member to limit both upward 30 and downward movement of the cage along the arm.

6. A carbonated water bottle filler, comprising a bracket, a flat, upwardly inclined arm fixed thereto to lie in a vertical plane, and having its 35 outer end twisted to lie normal to such vertical plane, a cradle member secured to the outer end of said arm to support the body of a bottle, a protective cage to enclose both said arm and a bottle disposed adjacent thereto, and a supporting ring secured to said cage and encircling said arm, of a size insufficient to pass over said cradle, but sufficiently large to slide freely along said arm, and said arm having a notch cut in the side thereof to receive said ring for supporting said cage in inoperative position hanging below said arm.

7. A carbonated water bottle filler, comprising a bracket, an upwardly inclined arm fixed thereto, a transverse member secured to the outer end 50 of said arm, a protective cage to enclose both said arm and a bottle disposed adjacent thereto, a supporting member secured to said cage and encircling said arm, of a size insufficient to pass over said transverse member, but sufficiently 55 large to slide freely along said arm, and means on said arm engageable with said supporting member to limit movement thereof downward along said arm.
